UNITED STATES PATENT OFFICE

113,387

DESIGN FOR AN AUTOMOBILE EMBLEM OR SIMILAR ARTICLE

George F. Kerr, Bronxville, N. Y.

Application October 6, 1938, Serial No. 80,288

Term of patent 7 years

To all whom it may concern:

Be it known that I, George F. Kerr, a citizen of the United States of America, residing at Bronxville, in the county of Westchester and State of New York, have invented a new, original, and ornamental Design for an Automobile Emblem or Similar Article, of which the following is a specification, reference being had to the accompanying drawing, forming a part thereof.

I claim:

The ornamental design for an automobile emblem or similar article, as shown.

GEORGE F. KERR.
